UNITED STATES PATENT OFFICE.

JOSEPH G. McGREGOR, OF OAK PARK, ILLINOIS, ASSIGNOR TO THE ADAMS & WESTLAKE COMPANY, OF CHICAGO, ILLINOIS, A CORPORATION OF ILLINOIS.

LAMP.

1,080,362.

Specification of Letters Patent.

Patented Dec. 2, 1913.

Application filed May 23, 1912. Serial No. 699,122.

To all whom it may concern:

Be it known that I, JOSEPH G. McGREGOR, a citizen of the United States, and resident of Oak Park, county of Cook, and State of Illinois, have invented certain new and useful Improvements in Lamps, of which the following is a specification, and which are illustrated in the accompanying drawings, forming a part thereof.

10 The invention relates to lamps especially adapted for switch and signal service in railroad work, and its object is to provide improved means for securely holding the font within the body of the lamp, consisting essentially of a font seat within the body, provided with parallel walls, and a font having side walls of complementary form, the walls of the font and seat having horizontal interfitting channels and ribs.

20 The invention is illustrated in the accompanying drawings, in which—

Figure 1 is a detail vertical section of the lamp, transversely of the font; Fig. 2 is a detail in perspective of the font; Fig. 3 is a detail in perspective of the lamp body with its side or font-receiving door open.

The body, 10, of the lamp, is ordinarily cylindrical in form, and is provided with a substantially flat bottom, 11, upon which 30 the font, 12, rests, and with walls, 13, 14, rising from the bottom and forming parts of the font seat, the upper sections of these walls being inclined laterally and upwardly, as shown at 15, 16, and joining the side walls 35 of the body.

The walls 13, 14 are horizontally channeled, as shown at 17, 18, and the side walls of the font are provided with ribs, 19, 20, adapted to fit within these channels and thus 40 prevent the font from being thrown out of the seat by jarring incident to service.

A spring catch, 21, secured back of one of

the walls, as 13, projects inwardly at the forward end of the wall, and is adapted to engage the outer end of the font when occupying the seat, and thus prevent its longitudinal movement.

The body 10 is provided with a door, 22, shown as adapted to slide upwardly, for the purpose of permitting the insertion of the font into the body.

In lamps of this character, it has been customary to employ a spring catch, such as shown and described, for preventing the longitudinal movement of the font, but no adequate provision has been made for preventing the upward movement of the font, and as the result, jars and vibration incident to service have frequently thrown the font out of position, and thus moved the burner, 23, 60 away from the axis of the lens, 24. In modern railroad practice, the lenses employed in this type of lamp have been perfected with a view to projecting the shaft of light in a definite direction, and for this reason it is of 65 vital importance that the illuminating agent be located directly upon the axis of the lens.

I claim as my invention—

In a lamp, in combination, a body, parallel walls rising vertically from the bottom 70 of the body and being spaced apart from the side walls thereof and having their upper portions extended laterally to the lamp body walls, a font having vertical sides and being of such width that it slidingly engages the parallel walls, said parallel walls 75 and the sides of the font engageable therewith having interengaging horizontal ribs and channels.

JOSEPH G. McGREGOR.
